UNITED STATES PATENT OFFICE

120,622

DESIGN FOR A SHINGLE

Frank Maurice Leslie, Oakland, Calif.

Application February 16, 1940, Serial No. 90,324

Term of patent 14 years

To all whom it may concern:

Be it known that I, Frank Maurice Leslie, a citizen of the United States, residing at Oakland, in the county of Alameda and State of California, have invented a new, original, and ornamental Design for a Shingle, of which the following is a specification, reference being had to the accompanying drawing, forming part thereof.

The figure is a plan view of a shingle, showing my new design.

I claim:

The ornamental design for a shingle, as shown.

FRANK MAURICE LESLIE,
